(57) **CLAIM**

I claim the ornamental design for a belly band with a structurally reinforced holster pocket, as shown and described.

DESCRIPTION

FIG. 1 is a perspective view of the belly band of my claimed design;

FIG. 2 is a front view of the belly band of FIG. 1;

FIG. 3 is a back view of the belly band of FIG. 1;

FIG. 4 is a top view of the belly band of FIG. 1;

FIG. 5 is a bottom view of the belly band of FIG. 1;

FIG. 6 is a left side view of the belly band of FIG. 1;

FIG. 7 is a right side view of the belly band of FIG. 1; and,

FIG. 8 is a view of the belly band of FIG. 1 being worn by a person.

The broken lines in FIG. 8 showing a gun, gun holster, and person illustrate environmental structures and form no part of the claimed design. The belly band with a structurally reinforced holster pocket is shown with a symbolic break in its length. The appearance of any portion of the article between the break lines forms no part of the claimed design.
